UNITED STATES PATENT OFFICE.

OSCAR C. BENHAM, OF DECATUR, ILLINOIS.

COMBINED SHADE AND CURTAIN FIXTURE FOR WINDOWS.

Application filed January 15, 1921. Serial No. 437,563.

To all whom it may concern:

Be it known that I, OSCAR C. BENHAM, a citizen of the United States, a resident of Decatur, in the county of Macon and State 5 of Illinois, have invented new and useful Improvements in Combined Shade and Curtain Fixtures for Windows, of which the following is a specification.

This invention has reference to combined 10 window-shade supports and curtain hangers, and its has for its principal object to provide a fixture of this character which is attachable to the window-frame without the use of nails, screws or tools of any kind, 15 and which is adjustable so as to adapt the fixture to different width window-frames and to different length window-shades.

The invention has for a further object to produce a fixture of the character referred 20 to made of complementary stamped elements whereby a very light, inexpensive and durable fixture is provided.

The invention has for a still further object to construct the supporting elements to 25 the fixture in a way that they will grip the opposite edges of the facing strips of the window-frame and held by means of springs which will cause a gripping action of the supporting elements on the frame.

30 That the invention may be more fully understood, reference is had to the accompanying drawings forming a part of this description, illustrating a preferred embodiment of the invention, in which:

35 Fig. 1 is a front face view of the upper part of a window-frame showing my fixture attached thereto;

Fig. 2 is a detail front face view of a 40 part of the facing strip of the window-frame showing an approximately full size view of the fixture;

Fig. 3 is an end view of Fig. 2 looking in at the right hand side of said Fig. 2;

Fig. 4 is a perspective view of a bracket 45 to receive the shade fixture and a curtain rod or pole;

Fig. 5 is a perspective view of a supporting bracket, and

Fig. 6 is a perspective view of a part of 50 a connecting and supporting bar.

Like characters of reference denote corresponding parts throughout the figures.

The window-frame is designated A having 55 the usual facing strips B.

1 denotes a supporting bracket, of which

there are preferably four for each window, and therefore the description of one will suffice for all. This bracket is preferably made of sheet metal and stamped out of a single piece. It is angular in form, having 60 the front and side plates 2 and 3. The latter at its rear edge formed with the angular bend 4 throughout its length having serrations, teeth or prongs 5 which are pressed into the edge of the facing strip 65 B, as shown in Fig. 2 to secure the brackets in place. The front plate 2 is stamped and bent so as to produce the hanger 6 which is bent outwardly, then upwardly, as shown in Fig. 5, and also the forwardly extended 70 finger 7 which is bent backwardly upon itself to provide the hook 8.

9 designates the shade and curtain rod or pole supporting bracket, which is also angular in form, and stamped so as to produce 75 the side plate 10 and front and rear parallel spaced plates 11 and 12. The inner end of the plate 11 is bent forwardly so as to provide a hanger 13 having the concave or dished upper edge 14 forming a seat for 80 a curtain rod or pole, shown in dotted lines, Fig. 3. The side plate 10 has a slot 15, or hole, in its upper edge, as the case may be, to receive the round or rectangular trun- 85 nion on the end of the shade roller, as will be understood. The rear plate 12 throughout its length at the top and throughout its length at the bottom, is formed respectively, with the curved and downwardly and outwardly inclined plate 16, and the rearwardly 90 extending substantially flat plate 17.

The supporting and connecting bar is 95 designated 18. This bar is preferably only long enough to extend across the front face of the facing strip B of the window-frame. The upper edge of the bar is curved to produce the downwardly and outwardly inclined plate 19, with which the plate 16 on the bracket 9 corresponds; and the lower edge of said bar 18 is bent to produce the 100 rearwardly extending substantially flat plate 20, with which the plate 17 on the bracket 9 corresponds. The brackets 1 and 9, as will be understood, are made in rights and lefts to provide pairs of each for the 105 opposite facing strips of the window frame, as shown.

When the pairs of supporting brackets 1 have been assembled in position on the facing strips B, a coil spring 21 has its oppo- 110

site ends looped over the hooks 8 on the supporting brackets 1 which draw the two brackets toward each other, firmly clamping the said brackets on the frame. The bars 5 18, if two are used, or the bar 18, if only one is used, will be clamped to the brackets 1 by sliding the same over the hangers 6. The vertical part of said hangers lies in juxtaposition to the rear face of the bar 18 10 with the plate 19 overhanging said hanger 6 and the plate 20 of the bar underlying the horizontal ledge of the hanger 6, as best seen in Fig. 3. The plates or strips 19 and 20 of the bar 18 are sufficiently flexible or 15 springy, whereby they may be pressed against the respective adjacent parts of the hangers 6 to impinge upon the same to hold the parts in assembled relation. The brackets 9 are carried by the bar 18 and have a 20 slidable relation thereon; the plates 12 of said brackets lying in juxtaposition to the outside face of the bar 18 with the plates 16 overhanging the plate 19 of the bar and the plates 17 underlying the plate 20 of the said 25 bar. The plates 16 and 17 are sufficiently flexible or springy, whereby they may be pressed against the respective adjacent parts of the bar to impinge upon the same to hold the parts in assembled relation.

30 From the foregoing description it is apparent that the supporting bar has a complementary relation with the hangers on the supporting brackets to slide thereon, and that the shade and curtain rod or pole supports have a complementary relation with the supporting bar to slide thereon. Such a structure not only makes a strong support-

ing fixture, but is adjustable for all intended purposes.

What I claim is:

1. In a combined shade and curtain fixture, in combination, a plurality of pairs of supporting brackets engageable with the sides of the respective facing strips of a window, each bracket provided with a hanger and a hook, a spring coupled to the hooks of each pair of said brackets to hold them in impinging relation with the respective facing strip, a supporting bar connecting said brackets and having parts 40 overhanging and underlying, respectively, said bracket hangers, and shade and curtain rod supporting brackets supported on said bar, and each having parts overhanging and underlying, respectively, said bar. 45

2. A combined shade and curtain fixture, including in combination, a pair of supporting brackets engageable with the sides of the facing strip of a window, each bracket provided with a hanger and a hook, a spring 50 coupled to the hooks of said brackets to hold them in impinging relation with said facing strip, a supporting bar connecting said brackets and having parts overhanging and underlying, respectively, said brackets, and a shade and curtain rod supporting bracket supported on said bar and having parts 55 overhanging and underlying, respectively, said supporting bar.

In witness whereof, I have hereunto 60 affixed my hand this 3rd day of January, 1921.

OSCAR C. BENHAM.
